UNITED STATES PATENT OFFICE.

MERTON T. STRAIGHT, OF ADEL, IOWA.

PHONOGRAPH NEEDLE OR STYLUS AND METHOD FOR MAKING THE SAME.

1,409,498.

Specification of Letters Patent. Patented Mar. 14, 1922.

Application filed July 6, 1920. Serial No. 394,373.

To all whom it may concern:

Be it known that I, MERTON T. STRAIGHT, a citizen of the United States, residing at Adel, in the county of Dallas, State of Iowa, 5 have invented a Phonograph Needle or Stylus and Method for Making the Same, of which the following is the specification.

My invention relates to styli for gramophones and particularly to those styli which 10 are adapted to be used in talking machines to reproduce sound from commercial sound record tablets. When a steel stylus is being used to reproduce sound from a sound record tablet, the tip or point of the stylus always 15 wears to a perceptible extent and a sharp edge is formed thereon which tends to cut and unduly wear away the walls of the grooves of the tablets and to produce a scratching sound. This wearing away of the 20 stylus point has a tendency to embed small particles of steel in the walls of the grooves and thereby increase the scratching noises and these embedded particles in turn tend to increase the wear on the points of the styli. 25 On account of the excessive wear of the stylus point and the wear on the sides of the grooves of the sound reproducing tablet, it is customary to use the steel stylus but once and when it has so been used, throw it 30 away and replace it with a new one. The necessity of having to change the stylus every time a record tablet is played, is annoying to say nothing of the liability of getting the used styli mixed with the unused 35 ones. Styli formed of a material softer than steel, such as tungsten, do not wear the sides of the sound grooves as much as steel stylus do, but have a tendency to wear blunt and thereby fill the small angular notches in 40 the grooves with the material worn from the stylus. On account of the small notches being partly filled and the blunt portions of the stylus having a tendency to ride over the smaller notches, some of the details of the 45 tones are sacrificed.

Therefore the object of my invention is to obviate the necessity of changing the stylus for each reproduction of sound from a record tablet and to produce a stylus of cheap 50 material and one that is comparatively inexpensive to manufacture which may be used to reproduce sound from a large number of tablets without substantial injury to the tablets and also to eliminate the scratching noise 55 without sacrifice to the quality of tone.

It is more particularly the object of my

invention to provide an improved method of producing gramophone styli from a natural deposited substance such as shale or clay and such as is described and illustrated in my 60 companion application on a phonograph needle or stylus and method for making the same, filed March 31, 1919, Serial Number 286,534.

Referring to the accompanying drawings: 65

Fig. 1 is a perspective view showing a block of natural shale from which my improved styli are made.

Fig. 2 is a perspective view of one form of a device for drying the blocks of shale. 70

Fig. 3 is a perspective view showing one of the shale bars ready for the shaping operation.

Fig. 4 is a diagrammatical top view showing the method of shaping my improved 75 stylus.

Fig. 5 is a side elevation of the same.

Fig. 6 is a plan elevation of one of the heat treating trays showing the styli in place.

Fig. 7 is a sectional view taken on the 80 line 7—7 of Fig. 6.

Fig. 8 is a sectional view taken on the line 8—8 of Fig. 6.

I have discovered that certain kinds of natural shale and clay possess the proper ingredients to make excellent styli for sound reproducing machines, capable of transmitting sound waves to the diaphragm in such a manner as to produce a mellow tone of fine quality and at the same time have a very 90 hard and smooth surface which does not wear when engaging the grooves of a sound reproducing record.

In making my styli, I preferably mine and cut the natural shale into rectangular chunks, 95 such as shown in Fig. 1 of the drawings. The blocks or chunks are then placed in a suitable drier such as shown in Fig. 2. This drier is provided with a series of shelves 10, formed of a series of slats 11, a heating device such as an electric heater 12, is provided below the lower shelf 10. The heater is to be equipped with the ordinary switches and controlling devices (not shown in the drawings) whereby the temperature may be regulated within the drier. 100

A ventilating device 13 is provided at the top of the drier and is provided with a slide 14, by which the circulation of air within the drier may be easily and quickly regulated. 110

It is important that the drying of the shale chunks be done very slowly so that

strains may not be set up within the shale due to contraction in drying. The drier is provided with a door 15 to provide for the placing and removal of the shale.

5 After the shale has become dried and hardened by the above process, I place the blocks one at a time in suitable cutters and cut them into pencils as shown in Fig. 3.

For forming the styli from the pencils, I 10 have provided a mechanism shown diagrammatically in Figs. 4 and 5, and having a rotatory shaft 17, grinders 18 and 19 and a cut off device 20. The shaft 17 is provided with a longitudinal opening 16 and is tapered at one end. Means not shown are 15 provided for supporting and rotating said shafts and grinders. The grinder wheel 18 is placed adjacent to the tapered end of said shaft, with the lower face of its periphery 20 slightly above the center of said opening 16, and is designed to rotate in the direction of the arrow. The pencils are ground to a cylindrical form by placing one of them at a time in the opening 16 and moving it longitudinally toward the grinder 18 while the 25 shaft 17 is being rotated, the pencil is thus forced under the grinder 18 which grinds it to a cylindrical shape. For pointing the stylus, I have provided the grinder 19 which 30 is placed with its face at a slight angle with the longitudinal axes of the shaft 17 as shown in Fig. 4 and at a distance ahead of the grinder a distance equal to the length of the desired styli. The axis of the grinder 35 19 is placed below the axes of the shaft 17 so that the periphery of said grinder is slightly above the cylindrical portion of the pencil and rotated in the direction of the arrow. This grinder 19 is so placed that 40 a point will be ground on the forward end of the pencil as it is fed forward. When it has reached the position shown in Fig. 5 a rapidly rotating cutter 20 is moved into engagement with the cylindrical portion of 45 the pencil vertically below the center of the grinder 18, and the stylus is thereby cut off. The cutter 20 is then moved downward and the pencil again moved forward for a new stylus.

50 The relative position of the grinder 19, as shown, is important. It will be noted that the motion of the particle of the grinder at the point where they engage the point of the stylus, are in a direction with the longitudinal axes of the rotating pencil and toward the body of the same. This permits the point to be ground without breaking it off. If the grinder 19 were so placed, the engaging particle of its face moved transversely 55 with the axes of the stylus or pencil, the point would then be broken off.

The same principle applies somewhat to the grinder 18 and for that reason the said grinder is rotated in the direction as indicated by the arrow.

The styli are now ready to be burned. To accomplish this without over-heating and burning the points, and to prevent bending and warping, I have provided a tray 22, provided with the side flanges 23 and a series of grooves 24 in the bottom. Each of these grooves is semi-cylindrical and tapered at one end to fit the point of the styli. A stylus is laid in each groove so that they will not bend or warp when heated. The flanges 23 are of such a depth that the trays may be stacked one above the other, and placed in the kiln for burning.

When the tray 22 has been filled with unburned styli I place them preferably in an electric kiln. Heat is then applied to gradually increase the temperature to a point slightly below that of melting. The heat is retained at that temperature for a short time, to permit the particles of the substances in the styli to settle together, after which the temperature is gradually lowered until cool, after which the trays may be removed and the styli packed for market.

I have found that styli thus produced 90 have the hardness about equal to that of a sapphire and have a very close-grained, smooth and polished surface.

The merit of my invention or discovery resides primarily in the method of providing a stylus by which the same, or better results, acoustically speaking, may be obtained as are obtained by the use of jewels, and at the same time provide such stylus at a cost which is merely nominal as compared with 95 the cost of jewels, thus resulting in a great saving of expense to the users of sound reproducing machines and at the same time gaining all of the advantageous results, both acoustically and mechanically speaking, as 100 are attained by the use of jewels, and avoiding the difficulties and disadvantages, both acoustic and mechanical, that are inherent in the cheaper materials that have heretofore been used for this purpose, such as the 105 necessity of frequently changing the styli, the injury to the records by the deposit of particles worn from the styli, and the defective acoustic properties thereof.

Another marked advantage of my invention 115 is that necessary shaping may be done upon the natural shale before it is vitrified, and this obviously can be done much more rapidly, efficiently and economically than could be done after vitrification. Furthermore in this connection, where the shaping of the stylus is done before it is hardened, then during the process of vitrification the exterior of the stylus becomes smooth, hard and tough, and far better for the purposes intended than if the shaping were done after hardening or vitrification.

I claim:

1. A method of making a sound reproducing stylus from natural shale or clay 130

which consists of cutting or grinding the natural shale into the desired shape, gradually heating to a point below melting and gradually cooling to a normal temperature.

5   2. A method of making a sound reproducing stylus from natural shale or clay which consists of gradually drying, cutting or grinding the natural shale into the desired shape, gradually heating to a point below melting and gradually cooling to a normal temperature.

10

3. A method of making a sound reproducing stylus from shale or clay which consists in cutting the shale or clay in bars, forming to the desired shape, gradually heating to a point lightly below melting and gradually cooling to anneal them.

4. The method of making sound reproducing styli from shale or clay which consists in cutting the shale to the desired shape, placing in fire proof molds to prevent warping and bending of the styli, then gradually heating to a temperature slightly below the melting point of the styli then gradually cooling to anneal them.

5. The method of making sound reproducing styli from natural shale which consists in cutting the shale in bars, drying the bars to harden or toughen them, then
30 cutting them to the desired shape, and placing in fire proof molds to prevent warping, then gradually heating the mold and stylus to a temperature where the styli will be
35 vitrified then gradually cooling to a normal temperature.

6. The method of making sound reproducing styli from natural shale which consists in cutting the shale in blocks or chunks, drying the blocks very slowly to harden and 40 toughen them, then cutting to pencil or bars and grinding to shape, placing in fire proof molds to prevent warping, then gradually raising the molds and styli to a temperature

slightly below melting and held at said temperature for a short time then gradually cooling to a normal temperature. 45

7. The method of making sound reproducing styli from natural shale which consists in cutting the shale into blocks or chunks, drying the blocks very slowly to harden and toughen them, then cutting to pencil or bars, grinding to cylindrical shape, pointing, and cutting off, placing in fire proof molds to prevent warping, then gradually raising the molds and styli to a temperature slightly below melting point of the styli and held at said temperature for a short time then gradually cooling to a normal temperature. 50 55

8. The method of making sound reproducing styli from natural shale which consists in cutting the shale into blocks or chunks, drying the blocks very slowly to harden and toughen them, then cutting to pencil or bars, grinding to cylindrical shape, pointing, and cutting off, placing in fire proof molds to prevent warping, then gradually raising the molds and styli to a temperature slightly below melting of the styli, then gradually cooling to a normal temperature. 60 65 70

9. The method of making sound reproducing styli from natural shale which consists in cutting the shale into blocks or chunks, drying the blocks very slowly to 75 harden and toughen them, then cutting to pencil or bars, grinding to cylindrical shape, pointing by grinding, and cutting off, the co-acting particles of the grinders moving longitudinally against that portion of the stylus to be sharpened, placing in fire proof molds to prevent warping, then gradually raising the molds and styli to a temperature 80 slightly below melting of the styli, then gradually cooling to a normal temperature. 85

MERTON T. STRAIGHT.
